ABSTRACT: An aerosol-type dispenser for dispensing a powdered material. The dispenser comprises a propellant container, valve means operatively associated with said propellant container for controlling release of propellant from said propellant container, and a product container for containing the powdered material to be dispensed. A propellant intake tube extends from said valve means into the lower part of said product container and has at least one opening at the end thereof opening out near the bottom of said product container. A discharge tube extends from near the bottom of said product container and out of the product container. A fluidization chamber is provided between said tubes and powder from the product container is fluidized and in said fluidization chamber by flow of propellant therethrough.

**AEROSOL-TYPE DISPENSER FOR DISPENSING A
POWDERED MATERIAL**

This invention relates to aerosol-type dispensers for powdered material and having a pushbutton-controlled valve. More specifically the invention relates to a lightweight, manually controlled aerosol dispenser for dispensing powdered material.

At the present aerosol dispensers are most commonly used for the spraying of liquids in the form of solutions, emulsions, or even liquid pastes. The devices are also used to spray fine powders in suspension in a liquid medium, but the concentration of such powders in the liquid medium usually does not exceed 15 percent for at a higher concentration the stability of the suspension would be jeopardized and there is a danger that the valve ducts will become clogged.

Attempts have been made to utilize aerosol dispensers of the conventional type for spraying powders. The dispensers had only one receptacle in which the liquefied gas and the active substance to be dispensed were mixed. However, the efforts were not entirely satisfactory, for it was found that the powder settles at the bottom of the receptacle and, as a result, when the valve of the dispenser is opened by pressing the pushbutton, the spray emitted consists essentially of the propellant gas alone. Consequently, the steady propulsion of a powder mist that was desired was not achieved.

To cope with these difficulties, it has been proposed in U.S. Pat. No. 3,289,949 to Roth, to spray powders by using an aerosol dispenser of a special type comprising, on the one hand, two containers, one to hold a liquefied gas serving as the propellant and the other to hold the powder to be sprayed, and, on the other hand, an obturating system controlled by a pushbutton. In the device disclosed in the Roth patent, the propellant draws the powder from said other container by means of a venturi effect at the moment of ejection of propellant from the one container. In this device the difficulties regarding the stability of the powder in suspension and the compatibility of the latter with the propellant are eliminated. On the other hand, the danger that the valve may be clogged by the powder continues to exist. In addition, certain other drawbacks may be encountered. For example, suction of the powder by a venturi effect causes waste of the propellant gas, because the gas stream aspirated from the powder container by the venturi, which is intended to carry the powder along with it, is only a small fraction, e.g. one one-hundredth or less, of the initial flow of the propellant gas. In addition the powder has a tendency to agglomerate and to clog the ducts, which are as a rule long and narrow, as the powder is aspirated at a relatively low speed of a few centimeters per second. Moreover, when a certain amount of powder has been aspirated, the powder remaining in the container has a tendency to bridge so as to form a sort of vault above the suction orifice, so that the powder no longer reaches this orifice.

Devices are known which improve the functioning of aerosol dispensers of the foregoing type, by which devices the powder is pushed forward by the propellant gas instead of being aspirated by it. In such arrangements, the propellant gas emerging from its container when the valve thereon is opened, is directed to the bottom of the powder container. This pressurized gas stream then has to pass through and fluidize practically the entire body of powder in the container before it escapes into the upper part of the powder container above the body of powder, carrying with it the powder picked up along its path. The mixture of gas and powder is dispersed to the outside of the dispenser in the form of a mist. This device has the drawback of being able to operate effectively only when the powder container has only a relatively small amount of powder therein. As a matter of fact, the gas stream which has to pass through the entire height of the stored powder rapidly loses its momentum and can then no longer fluidize the powder. Furthermore, with certain sticky powders, the gas stream eventually passes only through the channels that it has made in the stored powder and no longer carries any of it

away. For this reason, the mixture of gas and powder discharged from such a dispenser often does not have uniform proportions of gas and powder, which is another disadvantage.

Another proposal is to have a dip tube extending from outside the powder container into the mass of powder, which tube has apertures therein. Upon aspirating the powder by propellant from a separate propellant container atmospheric air flows through the apertures in the end of the dip tube, fluidizing the powder. Such an arrangement is shown in Abplanalp, U.S. Pat. No. 3,425,600. However, this arrangement will also result in channeling or bridging.

In order to secure better results, it has also been suggested to provide a tube for the intake of the propellant and the discharge of the propellant and powder mixture, which tube is generally U-shaped and is positioned in the powder container so that the curved section of the U is near the bottom of said container. In the curved section of said tube, close to the bottom of the powder container are two openings, both of which are oriented approximately toward the mass of powder above that section of the tube in a manner such that the central axes normal to these openings and to the longitudinal axis of the tube intersect at some distance above the curved section of the tube. In addition, a crimp is formed in the U-shaped tube, intermediate the two openings. In this arrangement, a major portion of the propellant will leave the upstream opening, i.e., the one on the inlet side of the tube, a certain amount of powder in the vicinity of this opening will be fluidized, and the resulting propellant and powder mixture will enter the second downstream opening on the other side of the crimp in the tube and be ejected from the top of the dispenser through the outlet branch of the U-shaped tube.

Tests carried out with such a device have shown that there is a strong tendency to form a bridge in the mass of powder and/or to clog the downstream opening in the tube with the powder. Also, even with smooth functioning, the powder-to-propellant ratio is at best only about 1:1.

It is one object of the present invention to provide an aerosol-type dispenser for powder which will permit the utilization of a large volume powder container and a liquefied propellant container the capacity of which is more or less the same but where the proportions by weight of the powder, and the propellant gas in the mixture driven toward the outside of the dispenser are much greater than those obtained with the above-described systems of known pushbutton dispensers for powder.

Another object of the invention is to provide an aerosol-type dispenser for powder in which the aperture for the outlet of the gas and powder mixture is not stopped up by the powder in the course of use, and in which the formation of bridges above the fluidization zone in the powder stored in the powder container is eliminated.

The aerosol-type powder dispenser of the present invention has two containers, one for the pressurized liquefied gas serving as the propellant and the other for the powder to be dispensed. The propellant container has a pushbutton valve which controls the flow of the propellant to an intake tube extending into the powder to be dispensed and opening out near the bottom of the powder container. A discharge tube is provided for conducting fluidized powder to the outside of the chamber. A fluidization chamber in which the propellant and the powder are mixed is located between the outlet mouth or nozzle of the propellant intake tube and an entrance opening provided for the discharge tube, this chamber being fed with powder from the powder stored in the powder container by gravity.

The dispenser according to the invention is characterized in that, in one embodiment, that has a partition separating said fluidization chamber from the rest of the powder container above it, this partition being provided with a sufficient number of holes to admit powder from the container. In this embodiment of the dispenser, the fluidization chamber is therefore an enclosed space positioned between the bottom of the powder container and, for example, a perforated plate forming the bottom of the powder storage space.

According to another, preferred embodiment of the invention, the fluidization chamber is enclosed, in the portion thereof which is located toward the aforesaid discharge tube, by a preferably funnel-shaped sleeve converging gradually toward and merging with the discharge tube, the wider entrance diameter of which sleeve is at least about five, and preferably 10 to 20 times larger than the diameter of the outlet mouth or nozzle of the propellant intake tube. The main portion of the jet of propellant leaving the said outlet mouth is directed toward and into said sleeve. Said sleeve envelopes a portion of the fluidization chamber and is either attached to the entrance opening of the discharge tube or is joined with the discharge tube, preferably as an integral part thereof.

Orientation of the jet of propellant toward the convergent portion of the fluidization chamber can be achieved either by aligning the outlet mouth of the intake tube more or less closely along the central axis of the aforesaid, preferably funnel-shaped, converging sleeve, or by so arranging the outlet mouth of the intake tube and the sleeve in relation to the container wall portion in the bottom zone of the powder reservoir that the container wall assists in guiding the jet of propellant through said fluidization chamber toward and into said converging sleeve.

This arrangement, according to the invention, of the fluidization chamber in the bottom zone of the powder reservoir makes it possible to avoid the above-enumerated drawbacks in the prior art devices and to attain powder-to-propellant weight ratios on the order of 7:1 to 10:1, and even higher.

In the most preferred version of the dispenser according to the invention, the volume of the fluidization chamber is a fraction of the volume of the powder container, and is bounded by the bottom of said container. The fluidization chamber comprises a section in open contact with the powder stock that is followed by a funnel converging toward the inlet aperture of the discharge tube.

Preferably, in all the embodiments, the dispenser comprises a pushbutton, including a head which, when at rest, closes the outlet end of the discharge tube. This head is equipped with a discharge nozzle which communicates with said outlet end only when the dispenser is actuated.

In all these embodiments of the dispensers according to the invention, the fluidization chamber, which has as small a volume as is possible, makes it possible for the jet of propellant gas emerging from the outlet mouth or nozzle of the propellant intake tube to expand gradually into a gas stream which travels a distance required to obtain a regular mixture of gas and powder. This powder-carrying stream is then forced into the discharge tube, at the end of said chamber, at the same rate that it is formed. This compact arrangement affords the advantage of instantly providing a powder mist as soon as the pushbutton is depressed, and of making optimum use of the kinetic energy of the propellant gas, losses of pressure being kept to a minimum.

The area of contact between the stored powder and this fluidization chamber is such that the feed of the powder is steady and almost independent of the quantity of the powder which is stored. The fluidization chamber thereby constitutes an autonomous device which, when the dispenser is actuated, operates independently.

For a liquefied gas reservoir having a normal capacity for a commercial aerosol dispenser, that is, equal to or less than 300 ml., and a powder container approximately 10 times larger, it is preferred that the volume of the fluidization space be less than one-third of the volume of the powder container.

Preferably, also, the average travel of the gas stream through the fluidization chamber should be between 1 and 8 cm., and the average cross section of this stream should be between 1 and 20 cm.².

Finally, and likewise preferably, the average area of contact between the powder stock and the fluidization space should be between 2 and 30 cm.².

Since all of the gas from the liquefied gas container is transmitted through the fluidization chamber, by making the propellant container the proper size relative to the amount of

powder stored in the powder container, it is possible to insure that all of the powder stored in the powder container will be dispensed. It has been found that an amount of powder up to 10 times the volume of the liquefied gas container can be dispensed.

The invention will be described in greater detail in connection with the accompanying drawings, in which:

FIG. 1 is a schematic elevational view, partly in section, of one embodiment of the powder-dispensing device according to the invention;

FIG. 2 is a sectional elevational view of another embodiment of the powder-dispensing device with the parts shown in the nondispensing positions;

FIG. 3 is a sectional view taken on line III-III of FIG. 2;

FIG. 4 is a sectional elevational view similar to FIG. 2 showing the parts of the device in dispensing positions;

FIG. 5 is a partial sectional elevational view of another embodiment of the fluidization chamber which can be used in the dispenser of FIGS. 2-4;

FIG. 6 is a longitudinal sectional view of another embodiment with two adjacent containers;

FIG. 7 is a horizontal sectional view taken on line VII-VII of FIG. 6; and

FIG. 8 is an axial sectional view of an embodiment of the upper portion of the dispenser.

In the embodiment shown in FIG. 1, the powder dispenser comprises a propellant container 1 for liquefied propellant gas C and a powder container 2 for powder B. The liquefied propellant gas container 1 is connected to powder container 2 by a fitting 3.

Liquefied propellant gas container has thereon a conventional type of valve which permits, upon actuation of a pushbutton 4, flow of a stream of propellant gas into a propellant intake tube 5.

Powder container 2 has an upper chamber 6, in which a powder B is placed, and a fluidization chamber A. Chambers 6 and A are separated from one another by a perforated plate 8 having openings 9 therein. Powder B gradually flows under the effect of gravity, from chamber 6 into fluidization chamber A through openings 9.

Propellant intake tube 5 passes through upper chamber 6 and perforated plate 8 through one of the openings 9 and at the end thereof has a mouth or nozzle 10 opening into fluidization chamber A.

The upper chamber 6 and perforated plate 8 are also traversed by a discharge tube 11 having an inlet 12 inside fluidization chamber A and an outlet in the form of a mouth or ejection nozzle 13 outside of powder container 2.

Pressing of pushbutton 4 sets in motion a flow of pressurized propellant gas which is conveyed through intake tube 5 into fluidization chamber A, where it expands greatly, fluidizing the powder in its path. This mixture of gas and powder, the pressure of which is higher than the atmospheric pressure outside the dispenser, is propelled toward inlet 12 of the discharge tube 11, into which it is forced and from which it emerges through ejection nozzle 13 in the form of mist.

The quantities of powder dispensed are progressively replaced by a fresh supply flowing from the body of powder B through openings 9 in perforated plate 8 by gravity.

With this embodiment of the dispenser according to the invention, with liquefied gas 1 of normal capacity not exceeding 300 ml., pure of mixed liquefied gases having a boiling point between 0° and -45° C. can advantageously be used as propellants. The following gases are preferred:

	Boiling point
Chlorodifluoromethane	-40.8° C.
Dichlorodifluoromethane	-27.8° C.
Propane	-42.2° C.
Isobutane	-11.7° C.
Butane	-0.5° C.
Isobutylene	-6.0° C.
Methyl oxide	-23.7° C.
Vinyl chloride	-14.0° C.

With a liquefied propellant gas container 1 of this kind, the flow should preferably not exceed 0.01 mole/second, because the cooling of the reservoir caused by quick evaporation of the liquefied gas results in a rapid decrease of the flow rate. This flow rate advantageously ranges between 0.01 and 0.001 mole and is preferably 0.005. With dichlorodifluoromethane, for example, these limits correspond to 1.2 and 0.12 g./sec., respectively.

The particle size of the powders to be dispensed can vary within wide limits, depending on the uses to which the powder is to be put. Preferably, the largest dimension of the powder particles is less than 0.15 mm.

In comparison with the pushbutton aerosol-type powder dispensers now known, this present embodiment of the invention permits significantly increasing the size of powder container 2, to a capacity of up to 3 liters. Such an arrangement makes it possible to spray larger quantities of powder without expenditure of any more liquefied gas than is used in conventional aerosol-type dispensers.

The numerous experiments which were conducted demonstrated certain relationships between various parameters of the dispenser which were desirable for ensuring optimum operating conditions with respect to both the quality of the spraying and the most efficient use of the propellant. For a liquefied gas reservoir having a normal capacity for a commercial aerosol dispenser, that is, equal to or less than 300 ml., and a powder reservoir approximately 10 times larger, these relationships are the following:

- a. the volume of the fluidization chamber must be less than one-third of the volume of container 2.
- b. the distance d of the average travel of the stream between the outlet nozzle 10 of the propellant intake tube 5 and the inlet aperture 12 of the discharge tube 11 must range between 1 and 8 cm.
- c. the total cross-sectional area of the openings 9 in perforated plate 8 must range between 2 and 30 cm.².

It has been established that in dispensers having these characteristics, the flow of the powder was always even and the mixture of gas and powder forced through discharge tube 11 contained between 75 and 90 percent by weight or powder.

FIGS. 2, 3 and 4 show another embodiment of the pushbutton aerosol dispenser according to the invention. A container 15 for liquefied gas C is positioned inside a container 16 for powder B. At the bottom of powder container 16 is a fluidization space A'. The container 16 has a cap 17 having depending from the center thereof a body 18 to which is attached a liquefied propellant gas reservoir 15 having inside it a valve to which a discharge nozzle 19 is attached. The valve is actuated by a pushbutton 20 which is movable downwardly against the discharge nozzle 19 through an opening 25 in the cap.

Pushbutton 20 comprises a head 21 and a depending shaft 22 having a recess 22a in which the hollow end of discharge nozzle 19 is engaged. A groove 23 is provided in shaft 22 and extending along the bottom and side of recess 22a and opening into body 18. The shaft 22 slides in the opening 25. A gasket 26 is inserted between the cap 17 and body 18, so that central cavity 24 in body 18 is sealed off from the outside. The shaft 22 preferably has an oval or polygonal cross section and opening 25 has a complementary shape in order to prevent shaft 22 from turning around its axis and to keep it oriented in one direction. Pushbutton 20 has an ejection nozzle 27 extending transversely thereof which is slightly inclined, to the horizontal. The nozzle 27 has a large aperture which opens at the periphery of head 21 and a small aperture at the outer periphery of shaft 22.

Fluidization space A' lies along the bottom of the powder container 16 and between a calibrated outlet mouth 28 of a horizontal portion 35 of a propellant gas intake tube 29 and an angularly disposed funnel 30 which converges toward intake 31 of a discharge tube 32. The inlet end of propellant gas intake tube 29 is positioned in a recess in body 18, which recess communicates with the central cavity 24 of the body. The discharge tube 32 has the outlet end mounted in a recess in

cap 17 which opens through a duct 33 into the opening 25 in the cap 17. Duct 33 is located in the axial plane containing the ejection nozzle 27 in the pushbutton 20. The two tubes 29 and 32 are kept a suitable distance apart by a bracket 34 resting on the bottom of powder container 16. Bracket 34 has a flange 34a thereon in which portion 35 of intake tube 29 is held.

When in the nondispensing position as shown in FIG. 2, pushbutton 20 is in a raised position. Outlet duct 33 opening into the opening 25 in cap 17 is covered and substantially closed by shaft 22 of pushbutton 20, thus closing the duct 33.

When pushbutton 20 is pressed down to the position of FIG. 4, displacement of discharge nozzle 19 releases gas from gas container 15. At the same time ejection nozzle 27 is brought into alignment with outlet duct 33.

The gas flows into cavity 24 in body 18 along groove 23, flows through propellant intake tube 29 and emerges in the form of a jet through calibrated outlet mouth 28. While expanding, this pressurized jet advances toward funnel 30, mixes with the powder which it encounters, and is then expelled through discharge tube 32, duct 33 and ejection nozzle 27 in pushbutton 20, carrying with it the powder with which it has mixed.

It will be seen that a fluidization chamber is actually formed in the space A within which the gas stream travels from its entry point to its exit point, which points are a distance d apart. In this space A, the amounts of powder fluidized are gradually replaced by the layers of powder which are around the upper periphery thereof, these layers moving downward under the influence of gravity.

According to this second embodiment of the invention, with liquefied gas container 15 with a normal capacity of 300 ml. at most, the liquefied gases that can be used are the same as those contemplated for the first embodiment. The same applies to the rates of flow from this reservoir 15 and to the size of the powder particles.

The second embodiment is a compact device, easy to carry and to handle. The outside container 16 can have a capacity that may range up to 3 liters. With a liquefied gas reservoir 15 of normal capacity of 300 ml., larger quantities of powder can be dispensed in an economical manner than with devices of the known type having an identical amount of liquefied gas. Moreover, according to this second embodiment, the outlet aperture of discharge tube 32 is closed during transportation and storage, so that loss of powder is eliminated.

The dimensional characteristics of fluidization space A in actual practice depend on spacing brackets 34 at an appropriate distance. Properly designed, the dispenser according to this second embodiment permits an even entrainment of the powder in the form of a mixture of gas and powder containing between 75 and 90 percent of powder.

FIG. 5 shows only the fluidization space A of another embodiment of the powder dispenser, the upper part of the dispenser being identical with the embodiment of FIGS. 2-4.

This embodiment differs from that of FIGS. 2-4 in that the axes of portion 35 of propellant intake tube 29 and of funnel 30a are parallel to the bottom of powder container 16 and in that portion 35 has a diverging branch 36 with a second outlet opening in the end thereof. This branch is oriented obliquely toward the layer of powder above fluidization space A. As before, intake tube 29 and the discharge tube are kept spaced apart by a bracket 34a.

This third embodiment operates in the same way as the embodiment of FIGS. 2-4. It is especially advantageous for the dispensing of sticky powders such as talcum, which are sprayed just as effectively as are less sticky powders. However, the powder container 16 has a slightly smaller capacity in relation to that of propellant container 15 on account of the diversion of some gas through the additional aperture in branch 36.

A fourth embodiment is illustrated in FIGS. 6 and 7. This embodiment of the powder dispenser according to the invention comprises a container 40 for liquefied gas C and a separate container 41 for powder B. These two containers are positioned coaxially and are capable of a slight relative axial

shifting movement allowed by connecting components (such as slides which are not shown). Propellant container 40 has an axial outlet valve 40a with a spray head 42 which is slidable in relation to the valve body. Spray head 42 is fitted tightly in an axial nozzle 46 in the bottom 45 of powder container 41. An axially disposed discharge tube 43 extends upwardly from the bottom 45 and has a funnel 44 on the lower end thereof. Slanting supporting legs 47 extending from the lower rim of funnel 44 to the bottom 45 and spaced outwardly from nozzle 46 support the discharge tube 43. At its other end, discharge tube 43 extends outside the powder container 41 and has an ejection nozzle 48 thereon.

As in the two preceding embodiments, the fluidization space A is located between nozzle 46 and funnel 44, and powder is fed into it by gravity, this feed being made possible by the open spaces between supporting legs 47.

When the two reservoirs 40 and 41 are brought closer together manually (e.g., by pushing reservoir 41 toward reservoir 40, which is assumed to be stationary), spray head 42 shifts position, which releases a stream of gas that emerges through nozzle 46 and brings about a fluidization in space A. The mixture of gas and powder is then formed into discharge tube 43, from which it emerges through ejection nozzle 48.

This fourth embodiment operates the same way as the two preceding embodiments. The length of supporting legs 47 is such as to provide the above-described spacing between the nozzle 46 and funnel 44.

FIG. 8 shows a modified arrangement for controlling release of propellant into the dispensing device described in FIGS. 2-4.

Cap 50 on the top of powder container 16 has a dependent portion 51 for carrying the liquefied gas container 15, and an elastic membrane 51a, integral with depending portion 51 is placed between the end of discharge nozzle 19 and the end of shaft 22 of pushbutton 20. The hollow end of the discharge nozzle 19 has a slot 52 therein through which a stream of propellant gas can flow. Shaft 22 of pushbutton 20 has an oval or polygonal projection 53 on the end thereof which fits into a seat 54 of similar shape provided in elastic membrane 51a, so that pushbutton 20 is free to move only axially of shaft 22.

This sealing arrangement has the advantage that it permits simplifying the manufacture of the dispenser according to the invention, since cap 50 serves at the same time as a holder for liquefied gas container 15 and has membrane 51a which is formed at the time of molding. No separate seal, such as gasket 26 in FIGS. 2-4 need be provided thus reducing manufacturing and assembly costs.

Examples of powders which can be dispensed with the pushbutton powder dispenser according to the invention are set forth hereinafter, merely to serve as illustrations of the manifold possible uses of the device according to the invention.

Example I—Fine-powder insecticide for the control of fleas lodged in old floors or on animals, or of bedbugs in beddings:

Ground DDT	5%
Ground lindane	1%
Talcum	94%

Example II—Fine-powder insecticide used more particularly for the control of roaches and ants:

0.0-diethyl and 0-(isopropyl-2-methyl-6-pyrimidyl-4) thiophosphate	2%
Talcum	98%

Example III—Fine-powder insecticide-fungicide for the protection of flowers, rose-bushes and shrubs against insects and diseases:

5,5-dimethyl-hydroresorcinol-dimethyl carbamate	1%
Lindane	1%
Copper oxychloride	2%
Sulfur	20%
Talcum	76%

Example IV—Antiperspirant powder:

Aluminum hydroxide	20%
Boric acid	2%
Talcum	45%
Colloidal kaolin	33%

Example V—Product for reducing friction in bearings of industrial machinery:

Finely ground molybdenum sulfide	100%

Example VI—Product in powder form for disinfecting garbage cans, sanitary equipment, rubbish piles, sewers and animal cages:

2,2'-dihydroxy-3,3'-5,5'-6,6'-hexachlorodiphenylmethane (G 11)	1.5%
5,5'-dichloro-2,2'-dihydroxydiphenylmethane (G 4)	1.5%
Talcum	50.0%
Colloidal kaolin	47.0%

Example VII—Dry colorant for stencilling:

Finely ground pigments	100%

Example VIII—Powder for drycleaning grease stains on clothing, chairs, draperies and wallpaper:

Absorbent synthetic silica	100%

Generally speaking, the pushbutton powder dispenser according to the invention permits distributing on any surface any finely ground active substance, with or without a filler, that is normally found in the solid state. Among these substances, classified according to use, the following may be cited:

Insecticides:	DDT, lindane
Fungicides:	Sulfur, copper salts, karathane
Herbicides:	Sodium chloride, aminotriazine
Bactericides:	Hexachlorophene
Bacteriostatic agents:	Penicillin
Foods:	Sugar, salt, dried pulverized plants
Colorants:	Pigments, dyes, opacifying agents
Rodenticides:	Coumatetralyl, Coumatophene
Cleansing agents:	Soap, solid detergents, absorbent powders, dry shampoos
Antiperspirants:	Aluminum salts
Lubricants:	Molybdenum disulfide, zinc stearate
Polishing agents:	Ground chalk, ground silica, corundum
Bonding agents:	Heat-sealing agents
Adhesion inhibitors:	Talcum, paraffin, flour
Drying or degreasing agents:	Absorbent synthetic silica
Scents:	Musk, menthol, dried pulverized plants

I claim:

1. An aerosol-type dispenser for dispensing a powdered material, said dispenser comprising a propellant container, valve means operatively associated with said propellant container for controlling release of propellant from said propellant container, a product container for containing the powdered material to be dispensed, a propellant intake tube extending from said valve means into the lower part of said product container and having at least one opening at the end thereof opening out near the bottom of said product container, a discharge tube extending from near the bottom of said product container and out of the product container, a sleeve-like member converging into the intake end of said discharge tube in the bottom of said product container and having a wide end facing toward the end of said propellant intake tube and being at least about five times the diameter of the one opening at the end of said propellant intake tube, said one opening at the end of the propellant intake tube being directed toward said sleeve-like member opening, the space between the opening at the end of the propellant intake tube and the sleeve-like member constituting a fluidization chamber in which the propellant and the powder are mixed and a bracket mounted on the inside of said product container, the sleeve-like member being mounted on one end of said bracket and the end of the propellant intake tube being mounted on the other end of the bracket.

2. A dispenser as claimed in claim 1 in which the axis of said sleeve-like member is angled downwardly toward the bottom and the center of said product container.
